UNITED STATES PATENT OFFICE

126,898

DESIGN FOR A JAR CAP LIFTER

Edmund B. White, Worcester, Mass.

Application January 9, 1941, Serial No. 97,942

Term of patent 14 years

To all whom it may concern:

Be it known that I, Edmund B. White, a citizen of the United States, residing at Worcester, in the county of Worcester and State of Massachusetts, have invented a new, original, and ornamental Design for a Jar Cap Lifter, of which the following is a specification, reference being had to the accompanying drawing, forming part thereof.

Figure 1 is a side elevational view of a jar cap lifter showing my new design.

Figure 2 is a top plan view thereof, and
Figure 3 is a front end elevational view thereof.

I claim:

The ornamental design for a jar cap lifter, as shown.

EDMUND B. WHITE.
